SKIRT AND GARMENT HANGER

Gerald L. Goetsch, Hartley, Iowa

Application May 21, 1948, Serial No. 146,508

Term of patent 7 years

(Cl. D80—8)

To all whom it may concern:

Be it known that I, Gerald L. Goetsch, a citizen of the United States, residing in Hartley, county of O'Brien, and State of Iowa, have invented a new, original, and ornamental Design for a Skirt and Garment Hanger, of which the following is a specification, reference being had to the accompanying drawing, forming part thereof, in which:

Figure 1 is a perspective view of the skirt and garment hanger, showing the arms in a retracted position; and

I claim:

The ornamental design for a skirt and garment hanger, as shown.

GERALD L. GOETSCH.
